STRIP METAL PACKAGE

John Ekern Ott, Lisle Township, Du Page County, Ill., assignor to Acme Steel Company, Chicago, Ill., a corporation of Illinois

Application March 25, 1939, Serial No. 264,255

6 Claims. (CL. 206—60)

This invention relates to improvements in strip metal packages and methods of forming such packages, and its purpose is to provide an improved package or bundle adapted to be readily moved about and to be shipped in freight cars and other carriers. The invention may be employed in bundling and shipping hot rolled and cold rolled strip steel and various other articles having similar shapes which are cut to substantially uniform length.

It has heretofore been the practice to ship hot rolled strip steel, and other articles having materially greater width than thickness and materially greater length than width, in bundles formed by piling a considerable number of strips upon each other flatwise in parallel relation and then securing them together by surrounding flexible binders formed of such materials as wire or flat steel strapping. Such bundles have been unsatisfactory because they readily bend and sag when they are picked up and transported by cranes or by workmen, with the result that the binders have become broken and the strips have "fanned" out and separated at the ends of the bundle or elsewhere, so that they have often been seriously damaged. These troubles have been particularly pronounced with bundles of strips of considerable length, such as sixteen feet or eighteen feet, for example, as it has been difficult to pick them up on account of their tendency to bend and they have consequently been dragged over floors and platforms with resulting breakage of the binders and damage to the surfaces of the strips.

The principal object of the present invention is to overcome the above mentioned difficulties, and others, by providing a new form of bundle or package which has beam-like rigidity throughout its length and is thus capable of being moved about by cranes or other devices without bending the strips which compose the bundle. More particularly, it is an object of the invention to provide an improved package or bundle of strip metal or other like objects comprising a plurality of sections bound together, each section comprising a plurality of strips which are arranged substantially at right angles to the planes of the strips of another section. A further object is to provide an improved method of bundling flat strips and the like according to which the strips are arranged in separate adjacent piles or groups with the strips in each group extending at right angles to the next adjacent group, after which the several groups are secured together by surrounding flexible binders to form a compact

bundle in which the tendency of the strips in any group to bend transversely of their own planes is overcome by the rigidity of the right-angularly disposed strips of an adjacent group. In forming such a bundle, the height of the pile of strips, in one group, is preferably substantially equal to the width of the strips in the adjacent group or groups, so that the bundle as a whole has a rectangular cross section. Still another object of the invention is to provide a new form of strip metal bundle adapted to be secured in unitary relation to one or more other similar bundles to form a compact load unit adapted to be shipped in a freight car or other carrier without the use of bracing, blocking or other securing means, according to the method described and claimed in the United States patent of Chester M. MacChesney and John Ekern Ott, No. 1,703,495. Other objects relate to various features of the improved package and to details of the method of forming this package which will appear more fully hereinafter.

The nature of the invention will be understood from the following specification taken with the accompanying drawings in which certain embodiments of the invention are illustrated. In the drawings,

Fig. 1 shows a perspective view of one form of package embodying the features of the present invention, with parts thereof broken away;

Fig. 2 shows an enlarged transverse section taken on the line 2—2 of Fig. 1;

Fig. 3 is a sectional view similar to that of Fig. 2 showing a modification of the invention in which the package is made up of four sections instead of three;

Fig. 4 is a perspective view, similar to that of Fig. 1, showing a modified form of the package of the present invention in which sheet metal protective caps are mounted over the ends of the package;

Fig. 5 is a perspective view of one of the protective caps which is mounted over the ends of the package illustrated in Fig. 4;

Fig. 6 is a perspective view similar to that of Fig. 1 showing another form of the improved package in which a protective covering of paper or the like is folded about the adjacent groups of metal strips; and

Fig. 7 is a perspective view of a package embodying another form of the invention in which the metal strips are enclosed in a wooden box before being bound together.

In the form of the invention shown in Figs. 1 and 2, the improved package 10 is made up of

three separate sections including a central section 10a and two lateral sections 10b. The central section is made up of a plurality of metal strips 11 or the like which are piled upon each other in superimposed relation with each strip extending in a horizontal plane and with the edges of each strip in alignment with each other. The strips of this section are preferably secured together by surrounding binders 12 which may be formed of pieces of wire having the ends of each piece twisted together after it has been drawn taut. Each side section 10b is similarly made up of a plurality of metal strips 11 which are preferably secured together by flexible binders 12 which are tied together with wire or the like. The strips 11 in the sections 10b are arranged in vertical planes so that they extend at right angles to the strips in the section 10a and a sufficient number of strips 11 are placed in the section 10a to cause the height of this section to equal approximately the width of the strips in the sections 10b so that when all of the sections are arranged adjacent each other, as shown in Fig. 1, they form a bundle of rectangular cross section. The sections of the bundle are bound together by surrounding flexible binders 13 which may be formed of steel strapping or the like and which preferably have wooden cleats 14 enclosed within them and extending across the upper and lower sides of the bundle. In this instance, there are three flexible binders 13 extending around the package, and after the binders have been drawn taut, their overlapping ends are secured together by sealed joints 15 which may be of the form disclosed in the United States patent to Ralph H. Norton, No. 1,260,016, or by any other joint suitable for the purpose. When the sections 10a and 10b have thus been bound together, they form a rigid package which may be lifted and transported without danger of bending any of the strips, since the strips of any section can not bend transversely to their own planes without bending the strips in an adjacent section in their own planes. The package thus retains a rigid beam-like form which resists relative movement of the strips.

In the form of the invention described above, the central section of the package contains more strips than either of the lateral sections but, if desired, the bundle or package may be made up of a number of sections which contain equal numbers of metal strips, as shown in Fig. 3. In this embodiment of the invention, the package 17 comprises two central sections 17a and two lateral sections 17b, the strips of each section being secured together by surrounding wires 18, or the like, which have their ends twisted or otherwise secured together. These sections may be formed in advance of such size that when the two central sections 17a are superimposed upon each other, their height equals approximately the width of the strips 19 which are employed in making the sections, thus producing a package of rectangular cross section. When the sections 17a and 17b have been arranged, as shown in Fig. 3, they are secured together by surrounding flexible binders 20, the ends of which are secured together by sealed joints 21. Wooden cleats 22 are preferably placed transversely of the package on its upper and lower sides within the binders 20. This form of package has the advantage that any sections may be selected from a group of previously prepared sections of uniform size and they are then arranged with the strips of two sections extending horizontally

and the strips of the other sections extending vertically. Of course, one lateral section 17b is sufficient to obtain the advantages of the invention, as the essential thing is that the bundle 5 comprise at least two sections which have their strips disposed at right angles to each other.

In Fig. 4 of the drawings, there is shown a modification of the invention in which the bundle 25 is made up of a central section 25a, which may include one or more separate groups of metal strips, and two lateral sections 25b made up of separate strips 26 which are similar to those embodied in the central section 25a, the latter section being of the same height substantially as the width of the strips 26. This package has the strips of each section secured together by surrounding binding wires 27 and the sections of the package are secured together by surrounding flexible binders 28 which enclose wooden cleats 29 and have their ends secured together by sealed joints 30. This package may be of the same form as those illustrated in either Figs. 2 or 3, except that the ends of the package are enclosed by cap members 31 which may be formed of waste sections of sheet metal which may be cut to have the form illustrated particularly in Fig. 5. Each cap member is shown as comprising two plates 31a and 31b which cross each other on an end of the bundle and terminate in flaps 31c and 31d, respectively, adapted to overlap the upper and lower surfaces, and the side surfaces, respectively, of the bundle. These cap members are adapted to be fitted over the ends of the package before applying the endmost binders 28 and the cleats 29, and when these binders are applied, the end portions of the flaps 31c and 31d are enclosed by the binders and the cleats so that they are held firmly in place to give protection to the ends of the metal strips 26.

In Fig. 6 of the drawings, there is shown a modification of the invention in which the metal strips are provided with a protective covering which is desirable particularly when shipping metal strips having a fine finish which must be preserved. The bundle 35 is made up of a plurality of metal strips 36 which are bound together in groups to form a central section 37a and two lateral sections 37b, the strips in the section 37a extending horizontally while the strips in the sections 37b extend vertically. As in the other forms of the invention, all of the strips are of substantially the same size and the central section 37a has a height equal to the width of the strips so that when the several sections are arranged in compact relation to each other, they form a bundle of rectangular cross section. The metal strips are provided with a protective cover 38 formed of heavy paper, cloth or the like, which is folded about the bundle with the outer longitudinal edge 38a of the strip located on the top of the bundle and with the folded end flaps 38b of the cover at the ends of the bundle reversely bent over the top surface of the bundle so that they extend beneath two of the wooden cleats 39 which extend crosswise of the bundle on the upper and lower sides thereof in pairs. The flexible binders 40, formed of steel strapping or the like, extend transversely of the bundle around the outer sides of the cleats 39 and their ends are secured together by seals 41. In this manner, the protective covering is held securely in place by the binders which serve also to prevent relative separation of the metal strips.

In Fig. 7 of the drawings there is disclosed a further modification of the invention which is particularly adapted for use in the shipment of cold rolled steel and the like. In this form, the bundle 45 includes a plurality of metal strips 46 of equal size which are arranged in three groups or sections 47a and 47b, the strips in the middle section extending horizontally and those in the two lateral sections extending vertically. In this case, the strips of each section are not bound together, but all of the sections or groups are placed in a wooden box 48 which is of such size that it is closely fitted by the groups of metal strips when they are arranged therein. This box may be formed in the usual manner of wooden boards which are secured together by nails 49 and after the metal strips have been enclosed in this box, a series of flexible binders 50 of steel strapping or the like are drawn taut around the outer side of the box. After being drawn taut, the overlapping ends of each strap 50 are secured together by seals 52.

Due to the rigidity of the packages or bundles which is obtained by the novel arrangement of the metal strips disclosed in the present invention, either of the bundles shown in Figs. 6 or 7 may be moved about and shipped without danger of destroying the coverings due to the bending of the metal strips, which is a difficulty which has heretofore been encountered in the shipment of metal strips to which coverings of paper or the like have been applied. The coverings of the present invention are retained in place without damage due to the distortion of the bundle so that the metal strips arrive at their destinations in the condition they were in when first arranged in the bundles. Although the invention has been described in connection with the shipment of metal strips, it is the intention that the invention may be practiced with various forms of flat or sheet material, such as lumber, paper-board, and the like, in connection with which the advantages of the present invention may be obtained by a relative right-angular arrangement of the flat members which are positioned in different sections of the bundle.

Although certain embodiments of the invention and certain examples of the improved method of forming the bundle of the present invention have been shown and described by way of illustration, it will be understood that the invention may assume various forms and that the method may be practiced in various ways coming within the scope of the appended claims.

I claim:

1. A bundle of flat flexible metal strips comprising a plurality of parallel sections bound together and each comprising a plurality of strips, the strips in each section being arranged parallel to each other and normal to the planes of the strips of another section with the longitudi-

nal axes of the strips in all of said sections extending parallel to each other, said strips in all of said sections being of the same size.

2. A bundle of flat strip material comprising a plurality of parallel sections arranged side by side in non-overlapping relation and bound together and each comprising a plurality of flat flexible metal strips, the strips in one section being arranged parallel to each other and transversely of the strips of an adjacent section, the strips in all of said sections being of the same size, the dimension of one section measured normally to the planes of the strips therein being substantially equal to the width of the strips in said adjacent section.

3. A bundle of identical flat flexible metal strips comprising a plurality of strips having their longitudinal axes extending parallel to each other and arranged with some of the strips extending edgewise to the planes of the other strips, cleats extending transversely of said strips, and flexible binders surrounding said cleats and said strips.

4. A bundle of identical flat flexible metal strips comprising a plurality of parallel sections each composed of a plurality of parallel sections each composed of a plurality of parallel strips, all of said strips having their longitudinal axes extending parallel to each other, the strips in one section extending in planes normal to the planes of the strips in another section, flexible binders surrounding the strips in each section, and other flexible binders surrounding the bundle to hold the sections together.

5. A bundle of flat flexible metal strips comprising a plurality of parallel sections each composed of a plurality of parallel strips, all of said strips having their longitudinal axes extending parallel to each other, the strips in one section extending in planes normal to the planes of the strips in another section, flexible binders surrounding the strips in each section, other flexible binders surrounding the bundle to hold the sections together, and cleats interposed between the last named binders and the sections and extending transversely of said strips.

6. A bundle of rectangular cross section of long flat flexible metal strips of rectangular shape comprising a plurality of parallel sections bound together and each including a plurality of parallel strips extending normally to the planes of the strips in another section, said strips in all of said sections being of the same size and being arranged with their longitudinal axes extending parallel to each other, the dimension of one section measured normally to the planes of the strips thereof being substantially equal to the width of said strips, whereby the bending of the strips in any of said sections transversely to their own planes is resisted by the strips in an adjacent section.

JOHN EKERN OTT.

CERTIFICATE OF CORRECTION.

Patent No. 2,328,356.

August 31, 1943.

JOHN EKERN OTT.

It is hereby certified that error appears in the printed specification of the above numbered patent requiring correction as follows: Page 3, second column, line 26-27, claim 4, after the word "parallel" strike out --sections each composed of a plurality of parallel--; and that the said Letters Patent should be read with this correction therein that the same may conform to the record of the case in the Patent Office.

Signed and sealed this 26th day of October, A. D. 1943.

(Seal)

Henry Van Arsdale,
Acting Commissioner of Patents.
